UNITED STATES PATENT OFFICE.

OTTO V. PETERSON, OF OAK PARK, ILLINOIS.

WINDOW-WASHER'S GUARD-CLAMP.

1,291,112.

Specification of Letters Patent.

Patented Jan. 14, 1919.

Application filed April 12, 1917. Serial No. 161,587.

To all whom it may concern:

Be it known that I, OTTO V. PETERSON, a subject of the King of Sweden, who has declared his intention of becoming a citizen 5 of the United States, and a resident of the city of Oak Park, county of Cook, and State of Illinois, have invented certain new and useful Improvements in Window-Washers' Guard-Clamps, of which the following 10 is a specification.

My invention relates to improvements in window washers' guard clamps and has for its object the production of a device of this character, which will be adapted for ready 15 and expeditious unlocking and release, and in which the movable locking pawl will be effectually guarded and guided in its pivotal movement.

A further object is the production of a 20 guard clamp of the character mentioned which will be of durable and economical construction, one which will be adapted for temporary support when not in use, and which, generally speaking, will be of high 25 efficiency.

Other objects will appear hereinafter.

The invention consists in the combinations and arrangements of parts hereinafter described and claimed.

The invention will be best understood by 30 reference to the accompanying drawings forming a part of this specification, and in which,

Figure 1 is a fragmentary transverse section through a window, in conjunction with 35 which is shown a window washer's guard clamp, embodying the invention.

Fig. 2 is a front elevation of the clamp 40 detached,

Fig. 3 is a partially sectional side elevation of the clamp, and

Fig. 4 is a central vertical section of the 45 clamp, showing the same engaged with the anchoring studs provided for engagement therewith upon the window frame.

The preferred form of construction as 50 illustrated in the drawings, comprises an elongated metallic body 5 provided at its rearward side with an elongated, longitudinally extending, downwardly opening slot 55 6. The slot 6 is adapted for engagement with the headed studs or bolts 7 which are provided in the frame 8 of the window in connection with which the guard is employed, as will be readily understood. The slot 6 is of a width to snugly receive the

shank or reduced portions of the studs 7, the heads of the latter being adapted to engage against the front side of the clamp body, as clearly illustrated in Fig. 4. 60

Pivotedly mounted upon the clamp body at the front side thereof, on a pivot pin 9, is a pawl 10 adapted, when in operative position, to engage behind or under the uppermost stud 7 engaged by the clamp, in 65 order to lock the clamp in engagement therewith, as clearly illustrated in Fig. 4. Said pawl is normally held in operative position by means of a helical compression spring 11 which engages against a finger piece or extension 12, formed upon said pawl, said portion 12 as well as the adjacent portion of the body of the clamp being formed with recesses 13 and 14, respectively, for the accommodation of the respective ends of said spring. 70

The outer side of the clamp body is recessed, as at 15, to accommodate the pawl extension 12 upon depression of the same. The arrangement is such, as will be seen, that the spring 11 is entirely inclosed, avoiding the 80 possibility of accidental displacement or injury which might result from exposure of the same. Formed at the lower end of the clamp body is an eye 16 adapted for engagement by the guard rope 16' with which 85 the clamp cooperates when in use. Formed at one side of the eye 16 is a second eye 17 adapted for the support of the water bucket 17' employed by the window washer, as clearly seen in Fig. 1. The eyes 16 and 17 90 are disposed forwardly of the plane of the rear face of the clamp body, so that, when the latter is engaged with the anchoring studs 7 of the window frame, said eyes will be spaced from the adjacent side of the 95 window frame so as to avoid any likelihood of the same being broken off and permit of ready and easy engagement with the eye 17 of the water bucket supporting hook. In guard clamps of this character, in use at 100 the present time, an eye similar to the eye 17 is employed, but the same is positioned at the rearward side of the clamp body where the same is exposed to knocks and jars frequently resulting in the same being broken off and in such a position as to render it difficult to engage the water bucket supporting hook therewith.

Formed at the upper end of the clamp, at the front side thereof, is a sort of housing 110 18, into the lower end of which projects the upper end of the pawl 10, said housing thus

serving as a guard or protection for said end of the pawl, and the sides of said housing serving as a guide to reinforce the pawl against lateral shifting, as will be readily understood. The front side of the housing 18 is formed with a downwardly opening slot or notch 19 adapted for engagement with a headed stud 19' provided upon the belt 19'' which is worn by the window 10 washer in order to temporarily hold or support the clamp, when the same is not in use. In clamps such as are used at the present time, no provision is made for the support of the same when out of use, and as a 15 result, the clamps are permitted to simply dangle at the ends of the guard rope. With applicant's arrangement, however, the clamp may be readily and easily engaged with the supports 19' upon the belt of the washer, 20 and thus conveniently held until again put to use.

With the construction set forth it will be seen that the pawl 10 may be readily and easily rocked to releasing position in order 25 to disengage the clamp by simply depressing the finger piece or extension 12 of the clamp, the latter being advantageously located for convenient engagement by the thumb of the user. In order to afford further means of 30 ready releasing movement of the pawl, the upper end portion of the latter is formed comparatively thick so as to afford comparatively wide lateral surfaces 20 adapted for ready engagement by the fingers of the 35 user. One side of the pawl is preferably formed with two recesses and the other side with a single recess, as clearly seen in Figs. 1 and 2, for ready accommodation of two fingers and the thumb of the user. The 40 clamps are used in pairs, one at each end of the guard rope, and the pawls used in the clamps at the opposite end of the guard rope will be similarly formed, that is, the recesses 20 will be arranged so that the 45 single recess or that adapted for engagement with the thumb of the user will be positioned at the side next to the user in both clamps.

While I have illustrated and described the 50 preferred form of construction for carrying my invention into effect, this is capable of variation and modification without departing from the spirit of the invention. I, therefore, do not wish to be limited to the

precise details of construction set forth, but 55 desire to avail myself of such variations and modifications as come within the scope of the appended claims.

Having described my invention what I 60 claim as new and desire to secure by Letters Patent is:

1. A window washer's guard clamp comprising an elongated body having a longitudinally extending slot at its rearward side opening at one end of said body, and 65 adapted to receive headed anchoring elements; a pawl pivotally mounted on said body adapted for engagement with an anchoring element engaging in said slot; a helical compression spring coöperating with 70 said pawl to normally hold the same in operative position, and registering recesses in said pawl and body engaged by and completely inclosing said spring, substantially as described.

2. A window washer's guard clamp comprising an elongated body having a longitudinally extending slot at its rearward side opening at one end of said body, and adapted to receive headed anchoring elements; a 80 pawl pivotally mounted on said body adapted for engagement with an anchoring element engaging in said slot; and resilient means entirely inclosed by said pawl and body coöperating with said pawl to normally hold the same in operative position, 85 substantially as described.

3. A window washer's guard clamp comprising an elongated body having a longitudinally extending slot at its rearward side 90 opening at one end of said body, and adapted to receive headed anchoring elements; a pawl pivotally mounted on said body adapted for engagement with an anchoring element engaging in said slot; and resilient 95 means coöperating with said pawl to normally hold the same in operative position, said pawl being comparatively thick to form comparatively wide surfaces for engagement by the fingers in rocking said pawl, substantially as described.

In testimony whereof I have signed my name to this specification in the presence of two subscribing witnesses.

OTTO V. PETERSON.
